UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

FLUID-PRESSURE-OPERATED HAMMER.

Application filed November 11, 1920. Serial No. 423,264.

My invention relates to fluid pressure operated hammers and the object thereof is to produce a simple and efficient hammer of this type used more particularly but not necessarily, as a sand rammer and characterized by a novel economical construction of parts and a new mode of operation, particularly as to the valve. Various features of advantage and utility in my new hammer will be apparent from the description hereinafter given.

In the drawings Fig. 1 is a central longitudinal section of a hammer embodying my invention; Fig. 2 a fragmentary sectional view substantially on the line 2—2 of Fig. 1; Fig. 3, an enlarged view of the rear portion of the hammer of Fig. 1; Fig. 4 an elevation of one end of the valve block; Fig. 5 a section of such block on the line 5—5 of Fig. 6; Fig. 6 an elevation of the other end of the block; Fig. 7 a section on the line 7—7 of Fig. 4; Figs. 8 and 9 sections on the correspondingly indicated section lines respectively of Fig. 6; Fig. 10 a detail view of the valve alone; Fig. 11 an elevation of the valve block cover; Fig. 12 a section on the line 12—12 of Fig. 11; Fig. 13 an elevation of the rear end of the cylinder; Fig. 14 an elevation of the rear end head or socket of the hammer.

Referring to the present embodiment of my invention as herein shown, the hammer comprises a cylinder or barrel 1, having a piston chamber 2 in which the piston 3 reciprocates, a valve block or box 4 located at the rear end of the cylinder and preferably provided with a separate lid or cover 5, a valve 6 reciprocable in the block and a head or socket 7 within which the valve and block are located and which engages the rear end of the cylinder for clamping the block in place at the rear end of such cylinder.

Referring in detail to the valve mechanism, the block is substantially truncated conical being provided with a valve chamber 8 and with three interior circumferential grooves 9, 10 and 11. The rear end of this valve chamber communicates constantly with the source of motive fluid admitted through the rear end of the head 7 by the pipe connection 12. By reason of the peculiar formation of the exterior of the block, there is formed between it and the interior of the wall of the head 7 an exhaust

chamber 13. The groove 9 is provided with one or more relief ports 14 communicating with the exhaust chamber 13 so as to permit of free movement of the valve. The groove 10 communicates with passages 60 15 which are here two in number and which extend through the lid 5 and through the walls of the cylinder to the forward end of the piston chamber where they emerge thereinto as ports 16. The groove 65 11 communicates with ports 17 which are here two in number and which pass through the lid 5 and part way down the walls of the cylinder until they emerge into the rear end of the piston chamber through the 70 ports 18.

The valve block is also provided with a series of passages 19 which are here four in number and which pass through the larger diameter portion of the block and 75 communicate freely with the exhaust chamber 13. These passages 19 also pass through the lid 5 and extend forwardly or downwardly through the walls of the cylinder and emerge at their forward ends through the ports 20 into the interior of the cylinder. These passages 19 also communicate with the piston chamber at the two points 21 and 22 located at different distances from the rear end of the cylinder. 85

The valve block is also provided with an inclined passage 23 extending from end to end thereof and communicating at its rearward end constantly with the motive fluid supply through the narrow space 23a. This 90 passage 23 extends through the lid 5 and communicates with a passage 24 in such lid which latter passage communicates at its inner end with the forward end of the valve chamber. These passages 23 and 24 95 thus form a by-pass between opposite ends or pressure areas of the valve. This passage 23 also communicates through the passage 25 with the piston chamber through a port 26 located at a predetermined distance from the rear end of the piston chamber.

The valve 6 is substantially a hollow cylinder closed at one end and provided with ports and grooves for the supply and exhaust of the motive fluid to and from the piston chamber. As shown, the valve is provided with a series of radial ports 27 communicating with the hollow interior 28 of the valve which is constantly supplied 105 110

with the motive fluid. The valve is also provided with the circumferential groove 29 adapted to span the groove 10 and radial ports 30 in the block, which ports communicate with one of the passages 19, also with the exhaust chamber 13. The valve is further provided with a series of radial ports 31, adapted to communicate with the passages 17 for supplying the rear end of the piston chamber with the motive fluid.

Describing a cycle of operation and starting with the valve and piston in the position shown in Figs. 1 and 2, the valve has already been shifted rearwardly and is now admitting the motive fluid from pipe 12 to the rear end of the piston chamber through the bore of the valve, ports 31, groove 11, passages 17 and ports 18. The piston is now ready to move forwardly and to deliver its blow through its shank or stem 32 which may be the work tool itself or to which a tool may be attached. At this time also the forward end of the piston chamber is at exhaust through the ports and passages 16 and 15, groove 29, port 30, exhaust chamber 13 and final exhaust port 33. The valve is held in this rearward position by the motive fluid admitted through the by-pass passages 23 and 24 to the forward or larger pressure area of the valve which operates in the forward end of the valve chamber. When the piston has moved forwardly so as to uncover the port 26, the pressure which has been built up in the forward end of the valve chamber will now be somewhat relieved, inasmuch as the pressure fluid will be free to enter the piston chamber instead of passing to the valve chamber alone, but it will not be relieved sufficiently to cause any shifting of the valve at this time. However, when the piston on its forward movement uncovers the port 21, the pressure in the rear end of the piston chamber will be initially exhausted or reduced to such an extent that the pressure in the forward end of the valve chamber will be relieved to such an extent below the line pressure that the motive fluid acting on the lesser or rearward pressure area of the valve will shift such valve forwardly. At this time the rear end of the piston chamber is placed at exhaust through the ports and passages 18 and 17, grooves 11 and 29, port 30, chamber 13 and exhaust ports 33. Also the forward end of the piston chamber is supplied with motive fluid through the ports 27, groove 10, passages 15, and port 16, with the result that the piston is moved rearwardly and as soon as it covers 26 the exhaust of the bypassed motive fluid through passage 25 ceases and pressure builds up behind the valve causing it to shift rearwardly and thus completing the cycle. The forward end of the piston chamber is exhausted not only through the port 16 but also through

the ports 21 and 22, until such time as the piston in its forward movement covers the latter. The relief ports 14 prevent any motive fluid being trapped so as to interfere with the ready shifting of the valve rearwardly.

The piston chamber at its forward end is provided with a packing 34, arranged between the two glands 35 which are held in position by means of the gland nut 36. One of the ports 19 extends as far as a port 20 for the purpose of supplying air through the passage 37, formed in the forward gland 35 through the space 38, and thence outwardly through the annular passage 36 around the shank 32, thereby supplying the motive fluid to the forward end of the tool for the usual purposes.

From the above it will be apparent that the disposition and arrangement of the by-pass passages 23 and 24 relative to passage 25, leading to the piston chamber, are such that a suction effect is produced in the forward end of the valve chamber when the rear of the piston chamber is open to exhaust, that the passages 23, 24 and 25 then in effect comprise an ejector for the forward end of the valve chamber, that the control of the outlet port 26 of passage 25 by the piston determines whether the live motive fluid continuously supplied by passage 23 shall build up pressure in the forward end of the valve chamber to shift the valve rearwardly or shall produce a suction effect to assist in the forward movement of the valve, and that the continuation of the suction effect through the action of the ejector provided by passages 23, 24 and 25 remains effective to hold the valve against rebound or fluttering directly, after the valve has shifted forwardly.

I claim:

1. A fluid pressure operated hammer comprising a cylinder having a piston chamber, a piston reciprocable therein, a valve block having a valve chamber and closing the rear end of the piston chamber, a valve reciprocable in the valve chamber and having a pressure area constantly exposed to the motive fluid supply and having a larger pressure area exposed to variable pressure, said hammer having a constantly open by-pass between said supply and said larger pressure area, and a passage from said by-pass to the rear end of the piston chamber, said passage being controlled by the piston in its reciprocations.

2. A fluid pressure operated hammer comprising a cylinder having a piston chamber, a piston reciprocable therein, a valve block having a valve chamber and closing the rear end of the piston chamber, a valve reciprocable in the valve chamber and having a pressure area constantly exposed to the motive fluid supply and having

- a larger pressure area exposed to variable pressure, said valve being in alignment with the piston chamber and shiftable forwardly by such constant motive fluid pressure, said 5 hammer having a constantly open by-pass extending from said supply and around the valve to the front end of the valve chamber, and also having a passage extending from the piston chamber through a port located 10 at a predetermined point from its rear end to said by-pass and thereby also communicating with the front end of the valve chamber, said port being controlled by the piston in its reciprocations.
- 15 3. A fluid pressure operated hammer comprising a cylinder having a piston chamber, a piston reciprocable therein, a valve block having a valve chamber and having a removable lid arranged at the rear 20 of the cylinder and closing the piston chamber, a valve reciprocable in the valve chamber and having at its outer end a pressure area constantly exposed to the motive fluid supply and a larger pressure area at its 25 other end exposed to variable pressure, said block and lid having a by-pass maintaining constant communication between the two pressure areas and the cylinder having a passage between the rear portion of the piston 30 chamber and the by-pass, said passage being controlled by the piston to control the shifting of the valve.
4. A fluid pressure operated hammer comprising a cylinder having a piston chamber, a piston reciprocable therein, a valve block having a valve chamber and having a removable lid arranged at the rear 35 of the cylinder and closing the piston chamber, a valve reciprocable in the valve chamber and having at its outer end a pressure area constantly exposed to the motive fluid supply and a larger pressure area at its other end exposed to variable pressure, said block and lid having a by-pass maintaining 40 constant communication between the two pressure areas and the cylinder having a passage between the rear portion of the piston chamber and the by-pass, said piston chamber having an exhaust port in its rearward portion and in advance of said passage and controlled by the piston to relieve 45 the pressure against the larger pressure area of the valve.
5. A fluid pressure operated hammer comprising a cylinder having a piston chamber, a piston reciprocable therein, a valve block having a valve chamber and closing the rear end of the piston chamber, a valve reciprocable in the valve chamber and having 55 a pressure area constantly exposed to the motive fluid supply for moving the valve in one direction and a larger pressure area for moving it in the opposite direction, said valve being in alignment with the piston chamber and being in the form of a hollow 60
- cylinder closed at one end and having ports and grooves for controlling the admission and exhaust of pressure to opposite sides of the piston, said hammer having a by-pass extending to said larger valve area, said by-pass having a constantly open motive fluid inlet of restricted size and a connection to the piston chamber under control of said piston, said connection being so arranged 65 relative to said by-pass as to make the motive fluid from the by-pass inlet operative to produce a suction on said larger valve area to assist in shifting the valve when the piston opens said by-pass to exhaust. 70
6. A fluid pressure operated hammer comprising a cylinder having a piston chamber, a piston reciprocable therein, a valve block having a valve chamber and having a removable lid arranged at the rear of the cylinder and closing the piston chamber, a valve reciprocable in the valve chamber and having a pressure area constantly exposed 75 to the motive fluid supply for moving the valve in one direction and a larger pressure area for moving it in the opposite direction, 80 said valve being in alignment with the piston chamber and being shiftable forward by such constant motive fluid pressure, said valve being a hollow cylinder closed at one end and having ports and grooves for controlling the admission and exhaust of pressure to opposite sides of the piston, said block and lid having passages uncontrolled 85 by said valve comprising a by-pass extending to said larger valve area, the block passage of said by-pass having a constantly open motive fluid inlet of restricted size, and a passage substantially in direct line with said block passage communicating with the piston chamber and controlled by said piston 90 thereby to effect a building up of pressure against said larger area to shift the valve when said last named passage is closed by said piston, the lid passage of said by-pass being at an acute angle to said block passage 95 thereby to produce a suction effect on said larger valve area and assist the smaller constant pressure area of the valve quickly to shift the same when the piston controlled 100 passage is opened to exhaust. 105
7. A pneumatic hammer having in combination a cylinder, a hammer piston, a valve for controlling said hammer piston, said valve having a working pressure surface, and means including fluid conduits 110 controlled by said hammer piston for alternately subjecting said working pressure surface to positive fluid pressure and to suction. 115
8. A pneumatic hammer having in combination a cylinder, a hammer piston, a valve for controlling said hammer piston, said valve having a working pressure surface, and means including fluid conduits for alternately subjecting said working pressure 120
- 125
- 130

surface to positive fluid pressure and to suction.

9. A pneumatic hammer having in combination a plurality of movable members one of which serves as a hammer piston and another as a valve, said valve controlling said hammer piston and having a pressure surface; and means including fluid conduits controlled by the movement of one of said members for alternately subjecting said pressure surface to positive pressure and to suction.

10. A pneumatic hammer having in combination a cylinder; a hammer, a valve, means providing an ejector having a discharge conduit communicating with the atmosphere by way of the hammer chamber of said cylinder, means for intermittently interrupting such communication; and said valve having a working pressure surface acted upon by gaseous fluid the degree of pressure of which is controlled by said ejector.

11. A pneumatic hammer having in combination a cylinder; a hammer, a valve, means providing an ejector cooperating with said valve, and means for alternately opening and closing the discharge conduit of said ejector.

12. A pneumatic hammer having in combination a cylinder, a hammer, a valve having a working pressure surface, means providing an ejector discharging into said cylinder and arranged for creating suction on said working pressure surface, an exhaust passage for said cylinder controlled by said valve, and said hammer controlling the discharge of said ejector into said cylinder.

13. A pneumatic hammer having in com-

bination a cylinder; a hammer, a valve for controlling said hammer, an exhaust port for said cylinder controlled by said valve, means controlled by said hammer for shifting said valve for opening said exhaust port, an ejector discharging into the atmosphere by way of said cylinder and said exhaust port, said ejector creating suction for holding said valve after it is shifted, and said hammer interrupting the discharge of said ejector when said valve is again to be shifted.

14. A pneumatic hammer having in combination a cylinder, a hammer, a valve, said valve having a working pressure surface effective to move the valve in one direction and a working pressure surface of different area effective to move the valve in an opposite direction, means for admitting motive fluid to said first surface, means providing an ejector for creating suction on said second mentioned area; and means for interrupting the discharge from said ejector for causing the building up of pressure on said second mentioned area.

15. A pneumatic hammer having in combination a cylinder, a hammer and a controlling valve, said valve having a forwardly acting working pressure surface and a rearwardly acting working pressure surface, and means for subjecting one of said surfaces to pressure fluid at high pressure for shifting said valve and the other to suction for locking said valve when shifted and for subjecting the latter pressure surface to positive pressure for overcoming the pressure on the first acting surface for again shifting said valve.

EDWARD W. STEVENS.
